INSULATED SHOE CONSTRUCTION

John Arnold Clark, Worcester, Mass.

Application September 16, 1950, Serial No. 185,209

2 Claims. (Cl. 36—2.5)

1

This invention relates to new and improved foot wear particularly of the sport wear type, such shoes generally being of heavier and stronger construction than ordinary shoes; the invention also includes lighter conventional constructions but is more particularly directed to the heavy type of shoe such as for sport and also including work shoes.

The principal object of the present invention resides in the provision of a completely waterproof shoe primarily made to give the maximum in protection to the feet and ankles under all conditions and at the same time to combine therewith the maximum of comfort so that the present shoe is actually more comfortable than a conventional shoe, it is completely insulated against cold or heat, it is snake bite proof due to the insulation, and it is completely waterproof although made of leather.

Another object of the invention resides in the provision of a shoe as above described in which the entire upper is made of leather insulated by a sheet of aerated latex such as Foamex, the insulating material being concealed by a leather liner and all seams of the shoe being completely waterproofed whereby the shoe is 100 per cent waterproof and may be immersed in water for many hours with no possibility of leaking; at the same time the shoe is extremely comfortable, due in part to the fact that the vamp comprises a plain soft leather toe as opposed to the moccasin type of toe so that it not only fits the foot better, but it lasts longer due to the omission of the usual moccasin seam and the construction of the present shoe results in an article of foot wear which is extremely long lasting and also extremely comfortable to the foot even under extremely adverse conditions.

Other objects and advantages of the invention will appear hereinafter.

Reference is to be had to the accompanying drawings in which

Fig. 1 is a view in elevation of a shoe according to the present invention;

Fig. 2 is a vertical cross section therethrough; and

Fig. 3 is a section on line 3—3 of Fig. 2.

As shown in Fig. 1, the preferred embodiment of the present shoe includes a relatively thick outsole 10 which is tough, flexible, long lasting and waterproof and is made from a rubber and cork composition so that it is also substantially non-slipping due to the presence of the cork particles scattered throughout the rubber. A heel 12 is provided, the same forming a breast 14 and

5 this heel may be made of any material but is preferably the same as that of the sole although it may have hollow spaces therein as indicated at 16 in Fig. 2. This breast provides an additional non-slipping means since when the wearer is walking in dangerous territory such as in a rocky stream, for instance, the usual fall is a forward slipping motion of the foot and the presence of the breast 14 enhances the chances of catching the foot on the rock or stone and stops or assists in stopping the forward slipping motion thereof.

10 The waterproof welt 18 is used at the line between the upper and the outsole, and the vamp 20 is soft and, therefore, comfortable to the foot in the complete absence of any kind of stitching although it is contemplated that the forward end of the toe at 22 could be reinforced or partially reinforced for rigidity at this point.

15 The shoe also has a quarter 24 and a gusset 26, the latter being attached to the former throughout the height thereof, so that the shoe is completely impervious to water throughout from the sole to the top of the shoe indicated at 28. Any form of lacing may be used, but this forms no part of the invention, the lacing being completely exterior of the gusset.

20 The shoe is made throughout from leather which is especially treated to begin with to make it waterproof; all the seams are completely waterproofed by waxing; the sole is waterproofed being made of rubber and cork; and the shoe is again treated for waterproofing after it is finished. By actual tests, these shoes have been worn in the water for over five hours with a complete absence of any kind of leaking whatsoever and this is the first shoe in the art of shoemaking which is completely waterproof although made of leather.

25 This results in a shoe which cannot draw the feet; the aerated latex and the leather will permit the passage of air but not water and, therefore, the shoe can "breathe" whereby perspiration of the feet does not cause clamminess as is a well known result from wearing all-rubber shoes.

30 Referring now to Figs. 2 and 3, the insole 30 is formed of a fairly thick piece of flexible leather having a filler 32 and a shank stiffener 34. The insole is provided with a lip 36 which is sewed as at 38 to the waterproof welt 18, the latter being doubled over as clearly shown and being absolutely watertight both due to the doubled over construction and waterproofing preparations with which it and the thread are treated.

35 Upon the insole there is a layer of aerated latex

40 which extends over the entire insole and which provides an extremely comfortable cushion for the foot as well as assisting in the prevention of the passage of heat or cold through the soles. A cover 42 is used on the latex.

The vamp of the shoe as at 20 comprises the outer leather layer 44 which is made of a completely waterproofed top grade leather which, however, is soft and flexible and underlying the same there is a vamp shaped layer of aerated latex 46 which is sewed in all the seams, see 38. Underneath the insulating material there is a cover 48.

The remainder of foot portion of the upper is also insulated either by a strip going around the heel from one side of the vamp to the other within the area indicated at 50 or an equivalent construction may be used in one piece with the quarter insulation 52 which extends throughout the entire leg portion of the shoe except for the gusset 26 which is provided with its own layer of insulation 54.

The strips of insulation are all included in the seams throughout the shoe which additionally reinforces and waterproofs the same and at the same time assures 100 per cent insulation. There is no point or area throughout the entire shoe which does not have the insulation material above described and, therefore, the foot is completely encased in a layer of aerated latex which makes the entire shoe soft to the foot, even though exactly fitting the same.

The construction of the shoe will be seen to those skilled in the art and particularly to outdoorsmen and others who wear heavy footwear, including working shoes, that the same is rugged, long wearing, comfortable, waterproof and extremely snug without any clamminess as would be the case with rubber footwear and without any breaking-in period required. The entire sole although very thick, is quite flexible and the shoe feels when first put on as though it were an old shoe which had been worn a long time. The non-rigid construction particularly in the toe area and throughout the vamp ensures that the shoe will conform to the foot and by eliminating the usual moccasin seam and due to the new construction, the shoe is much longer lasting and more rugged.

Also, the counter 56 and insole alone may be cushioned, as in slippers, golf and other sport shoes, hunting and fishing boots, sierra sporting boots, officers' shoes and boots, and loafers. Any conventional street shoe may be made according to the present invention, which is not limited to the types described, but may apply to any shoe.

In cases where the shoe is fully insulated, the

shoe may be made as an all-weather boot, arctic, jungle, or snake boot, or as a Canadian caper or folk dancer shoe or boot.

Having thus described my invention and the advantages thereof, I do not wish to be limited to the details herein disclosed otherwise than as set forth in the claims, but what I claim is:

1. A shoe of the class described comprising a sole including a rubber composition outsole and an insole having a layer of soft, compressible, insulative material thereon, a vamp including a vamp-shaped layer of the said material, and a quarter, the quarter portion of the shoe including a layer of said insulative material, all of said soft, insulative portions being overlapping in such a way that the entire foot portion of the shoe is completely insulated, and a gusset including a layer of soft insulative material so that the ankle portion of the shoe is completely insulated, all the layers of the insulative material being sewed together at contiguous edges to overlap.

2. A waterproof shoe of the class described comprising a composition outsole, an insole, a layer of aerated latex on the insole, a vamp, a layer of aerated latex under the vamp, and a quarter, there being a layer of aerated latex in the quarter, the vamp latex layer extending below the top surface of the insole and being sewed thereto, and a waterproof seam about the upper and outsole, the stitching through the vamp latex layer extending therethrough.

JOHN ARNOLD CLARK.
